DEVICES FOR INCREASING LUMINOSITY

Jacques Claude Vulmiere and Huguette Vulmiere, née Grangaud, Pre-Saint-Gervais, and Max Fourestier, Vanves, France, assignors to Centre National de la Recherche Scientifique, Paris, France, a corporation of France

Filed Dec. 7, 1956, Ser. No. 626,874

Claims priority, application France Dec. 9, 1955

11 Claims. (Cl. 313—112)

The present invention relates to a device for increasing the luminosity of incandescent lamps having polished emitting surfaces, for example with tungsten filaments or tapes, or with diffusing emitting surfaces, for example with opaline bulbs, with Nernst or Globar rods.

The invention also enables the luminosity to be made uniform, particularly in the case of the tungsten filament lamps of the type used in cinematograph projectors.

Up to the present time, certain well-known optical methods have been proposed in order to obtain an increase in the efficiency of an incandescent source. Being provided solely for lamps with coiled tungsten filaments, they are intended to form an image of the filament on itself in order to attempt to fill in the gaps between the filament spirals.

To this end, there is employed either a mirror which is centered on the filament and having an opening equal to that of the condenser which is placed in front of the source, or the bulb itself is partly silvered, provided always that it is spherical and centered on the filament.

In practice, under the best conditions of construction, the average increase in luminosity obtained does not exceed 30%. This is due to the fact that the existing types of lamps being tightly coiled, there are very few and very small gaps between the spirals of the filament, and also that these gaps cannot be entirely covered by the inverted image of the filament, since it is not possible to obtain such a perfect uniformity of winding in spirals as would make the image identical with the object.

It has also been proposed in the case of spherical bulbs, to silver them almost entirely while forming a window corresponding to the opening of the condenser. The silvering, the bulb and the filament do not however withstand the high temperatures to which they are thus subjected, and it has therefore been proposed to enclose these lamps in an indestructible spherical cap of small size, placed against the bulb. However, this chamber forms in fact a calorimeter and the increase in temperature is very great. In order to obtain an acceptable life for these devices, certain authors have proposed the use of the above assembly while considerably underrunning the filament (by about 20%). It is thus not a matter of increasing the luminous intensity, but simply of reducing the necessary electrical power while maintaining the real temperature of the filament by virtue of the temperature rise in the chamber which is not ventilated.

The present invention has the feature in common with the above methods, of utilising reflecting systems around the source of light. As will be seen in the description which follows, however, the objects, the numerical results, and the practical method of construction are very different. The present invention is applicable to a large number of types of lamp in the region of the visible spectrum and also outside this region. It has already

been employed under practical conditions by the present inventors with success.

It will be remembered that the luminous energy of a polished tungsten element at an absolute temperature T is less than that of a black body at the same temperature T . The same thing is true for a Nernst or Globar filament.

In the case of tungsten which, in the visible spectrum, is substantially a grey body, the luminous energy is, in this region about four-tenths of that of the black body. It is one-third at about 1 micron, one-quarter at 2 microns and one-fifth at about 3 microns.

In the case of the Nernst filament which is preferably employed between 3 and 7 microns, this difference is large, since in this region it attains one-tenth to one-twentieth.

This shows the great advantage which it is possible to gain by transforming a given source to a source equivalent to the "black body" of the same surface area and the same real temperature.

A substance such as tungsten has, when hot, if it is polished, a high reflecting power which is substantially constant in the visible spectrum and equal to 0.5 after which it increases rapidly in the near infra-red and exceeds 0.9 beyond 2 microns.

In the case of a rod of the Nernst type, the same phenomenon is found, as far as its diffuse reflection factor is concerned, which is in the vicinity of 1 in the near infra-red.

To sum up, whether it is polished or diffusive, a filament brought up to incandescence can be considered, at the same time as a source possessing a luminous energy proper L , and as a mirror or a diffusing screen having a reflecting power R when hot.

The above observations have led the inventors to the idea of constructing a device for increasing the luminosity of incandescent lamps, such as has been referred to above. To this end, it is proposed to utilise the luminous energy which is not directly employed by the condenser to form the image of the filament strictly and exactly on itself, by means of a suitable optical system. If part of the reflected rays is located in the direction of observation, the apparent luminosity of the corresponding part of the filament becomes $L(1+R)$, neglecting the losses due to the optical system. This is the sum of the luminosity proper of the filament and of the luminosity of the image reflected by the filament.

If the optical device enables the number of successive reflections on itself and on the filament to be increased, the apparent luminous energy of the filament will tend towards the limit:

$$L(1+R+R^2+\dots), \text{ or } L\left(\frac{1}{1-R}\right)$$

For a given wave-length, the coefficient of increase of the luminous energy will tend:

For $R=0.5$, towards 2

For $R=0.75$, towards 4

For $R=0.9$, towards 10

In order however to obtain such an efficiency, the optical device associated with the source considered as a mirror or as a diffusing screen should be capable of giving a large number of multiple reflections, and this with a minimum of loss due to this device. This is one of the essential objects of the invention.

In other words, the invention consists in transforming the emitting source at a true temperature T to a source having an identical surface area, the useful aperture of which can easily attain 60° , the properties of which, from the point of view of emission energy are in the

vicinity of those of the "black body" at that same temperature T , practically unchanged, and this without substantial modification of the power required for the supply of the incandescent filament.

In accordance with the invention, the device having a uniformly-distributed high luminosity, comprising a filament or strip and means for reflecting the light emitted by the filament in a desired direction, is characterised by the fact that the said reflecting means are surfaces of large dimensions, centered on the filament or the like, are non-diffusing and have a reflecting power as high as possible in the region of the spectrum employed, and that, with respect to the source, the said reflecting means are in a position such that the luminous energy is as close as possible to that of the black body at the same temperature.

In order to obtain the best results under the general conditions indicated above, the assembly of the elements of the device should be such that the spherical aberration in the vicinity of the centre of curvature is very small, which leads in practice to a diameter of the sphere greater than 60 mm. At the same time, the diffusion should be a minimum and the sphericity should in consequence be perfect with an excellent polished surface. The reflection factor of the system should be as close as possible to 1 in the field of the spectrum employed, which necessitates a suitable choice of the reflecting material to be deposited. The centering of the source in the sphere should be perfect.

In order to obtain these results, it is possible to couple together two metallic half-spheres on the internal surface of which there has been deposited a reflecting layer or coating.

It may be preferable to replace the two metallic half-spheres by half-spheres of glass such as that known under the registered trademark "Pyrex" or, better still, by transparent optical silica which resists thermal shocks, the half-spheres being metallised as may be required on their convex or concave sides.

It is essential to provide an efficient cooling for the glass bulb, which absorbs practically all the infra-red rays beyond 2 microns, and this can easily be effected with the device in accordance with the invention.

The source of light may be a metallic filament or strip, preferably of tungsten, having in known manner a high strength in the vicinity of its supports. As diffusing sources, there may be employed either opalescent lamps or filaments with Nernst or Globar rods.

The accompanying drawings show various forms of embodiment of the devices in conformity with the invention. In these drawings:

Figs. 1 and 2 illustrate the case of a strip-filament lamp, respectively in a horizontal cross-section view and a view in perspective, of a first form of embodiment of the invention.

Figs. 3 and 4 show two views of an alternative form in cross-section made respectively along two planes at right angles.

Fig. 5 is a view in cross-section of a lamp in accordance with the invention which permits of an easy cooling, without considerable bulk.

Fig. 6 is an alternative form of the device shown in Figs. 3 and 4.

Fig. 7 shows an alternative form of the device shown in Figs. 1 and 2.

Fig. 8 is a diagrammatic view of an assembly with an opaline source.

In the form of embodiment of Figs. 1 and 2, the incandescent strip or ribbon 1 is placed at the centre of a spherical mirror 2. Observation is made in the direction 3, symmetrical with the axis 4 of the mirror 2 with respect to the perpendicular XX' passing vertically through the centre of the incandescent ribbon. On a lens 5 which has as its axis the direction 3, there is received on the one hand the direct radiation emitted by the strip 1 and,

5 on the other hand, the radiation emitted by the strip in the direction of the mirror, which radiation has been reflected at least once on the mirror 2 and then on the strip 1. In order to collect this radiation under good conditions, whilst avoiding stopping-down to a "cat's eye," the lens 5 is given an opening slightly less than that of the mirror 2.

10 As the luminosity of tungsten in the hot state does not follow Lambert's law, but varies with the incidence so as to reach a maximum towards 70°, the angle of the axes of the mirror 2 and of the condenser 3 with XX' is chosen or calculated so as to obtain a maximum luminosity by using the best portion of the curve of variation of the luminosity of tungsten as a function of the incidence for a given opening of beam.

15 The mirror 2 may be replaced by a lens 2' (see Fig. 7) and a plane mirror perpendicular to the axis forming an auto-collimator system on the filament. A colored glass 2'' may be placed in a manner inclinable at will on the axis in front of the plane mirror, between the said mirror and the lens, that is to say in order to keep the beam parallel so as to cause the thickness of the glass passed-through to vary, to modify the coloration of the reflected beam and, in consequence, to modify the 20 color temperature of the overall beam employed. In this way, there can be obtained a variable colored brilliance which is greater than the brillance of the filament itself.

25 When a tungsten filament is used as a source with a continuous spectrum, by employing an auxiliary monochromatic lamp with spectral lines, reference marks of pre-determined wave-lengths can be projected on the continuous base provided by the filament.

30 In accordance with the form of embodiment shown in Figs. 3 and 4, the lamp 6 has its filament 7 located at the centre of a spherical mirror 8; the filament is preferably provided with a number of rows of coils. The mirror is formed by two members 9 and 10, of metal, or of transparent silvered optical silica, the internal spherical surface of which is reflecting and is very precisely centered on the filament. Its radius is made sufficiently great for the aberrations of the images of the edges of the filament to be negligible, these images being formed in the vicinity of the centre of curvature. Cylindrical openings 11 and 12 permit of the passage of the base and of the upper portion of the lamp, together with the flow of cooling air.

35 The two members 9 and 10 are each provided with a flanged portion 13, 14 and are connected together for example by means of screws. This permits of easy dismantling for changing the lamp, whilst ensuring a correct position during re-assembly. A cylindrical opening formed in the members 9 and 10 provides the housing for a condenser 15. The socket of the lamp, not shown on the drawing, is provided with the desired adjusting devices which will permit of the perfect centering of the 40 filament at the centre of the spherical mirror.

45 Fins 16 help in ensuring the cooling. This cooling can be further assisted by a forced ventilation which will follow the direction of the arrows F.

50 For large outputs, lamps with external bulbs can be used, such as shown in Fig. 5. The portion located in the interior of the reflecting sphere is of small dimensions and the cooling will be effected, not only by a flow of air following the path of the arrows F, but also by the movements of convection of the gas inside the bulb, of which 55 a part 17, located outside the reflecting chamber, is in direct contact with the air.

56 This device is especially utilisable in cinematographic projectors; the spherical mirror transforms the source of light to a black body, fills in the gaps between the spirals and improves the uniformity. Thus the image is formed closer to the film by using only the central coils at high temperature. The coefficient of increase obtained is of the order to 4 to 5.

60 Fig. 6 relates to the case in which the source of light 75 is a spherical bulb with a bunched filament (one single

coil of closely-wound turns). An external spherical mirror may be used, leaving as openings only those required for the passage of the bulb and of the condenser. In certain cases, in order to reduce the overall bulk of the system, it is preferable to use, not a single sphere, but portions of spheres having different radii, these various portions being accurately centered on the filament. A system of this kind is essentially formed by two spherical mirrors 18 and 19 of the same radius and an element 20 having a smaller radius. This element 20 has the same openings as the condenser 15. It does not play the same part as the mirrors 18 and 19, but serves only to send back to the condenser the light flux which it receives; for that reason, it may be slightly polished.

This bunched filament device may be employed either for normal working:

In the visible spectrum; the mean luminosity is multiplied by about 3;

In the infra-red spectrum (towards 1 micron to 1.5 microns) the luminous energy is multiplied by about 4 or 5, which gives very good possibilities for infra-red projectors using receivers with photo-electric cells or image transformers;

Or for working with excess voltage in the vicinity of the melting temperature of tungsten, there is obtained a luminosity in the red very close to that of the electric arc: this is a greater and important advantage in medical photography; for example with an endoscope or a retinograph, or a slot lamp.

A lamp with an opaline bulb 21 may be employed, for example for the enlargement of photographic negatives 22 (see Fig. 8), the summit of the lamp being centered on the mirror. There may also be employed as a source a lamp with a Nernst filament with its axis on the reflecting sphere; in accordance with the oxides employed for the rods, there is obtained a coefficient of increase of 10 to 20 for the spectral region of 1 to 7 microns.

It can be seen that the device in accordance with the invention enables the luminosity of an incandescent lamp to be increased by observing a portion of filament or of strip which emits, in addition to its own radiation, a reflected radiation derived either from another portion of the filament or strip, or from the same portion of the filament or strip but after at least one reflection on a mirror.

It has been found that in all cases, the device in accordance with the invention ensures a very large number of multiple reflections with the minimum of loss inherent in the apparatus. In practice, the devices which have been described above generally enable the brilliance to be multiplied by a coefficient comprised between 3 and 20, depending on the cases and the field of the spectrum in which the work is carried out.

The device in accordance with the invention finds its applications, inter alia in projectors, projection apparatus for cinemas, lighting devices for microscopes, endoscopes, profile projectors, slot lamps, retinographs, searchlights, electronic projectors for barrages, etc.

What we claim is:

1. An optical illuminating system having a high and uniform luminosity, comprising an incandescent element constituting a source of radiation; an envelope containing said element; means of optical quality in the path of visible radiation from said element for reflecting such radiation and forming a reflected image of said incandescent element strictly and exactly on said element, said means comprising a spherical optical surface of large dimensions perfectly centered on said incandescent element and having a radius such that spherical aberrations close to its center of curvature are substantially smaller than said incandescent element; and a condenser adapted to collect radiation from said source, the axis of said condenser intersecting the axis of said incandescent element at the center of curvature of said surface; whereby the total luminous energy collected by said condenser is

the sum of the direct radiation thereto from said element and the multiple reflections by said means of radiation from said element, and approximates that of a black body at the same absolute temperature as said element.

5 2. An optical illuminating system having a high and uniform luminosity, comprising an incandescent element constituting a source of radiation; an envelope containing said element; means of optical quality in the path of visible radiation from said element for reflecting such

10 radiation and forming a reflected image of said element strictly and exactly on said element, said means comprising a spherical optical surface of large dimensions perfectly centered on said element and having a radius such that spherical aberrations close to its center of curvature are substantially smaller than said element, said

15 means including a lens providing said spherical surface and a plane mirror positioned perpendicular to the axis of said lens to form an auto-collimator system on said element; and a condenser adapted to collect radiation from said source of radiation, the axis of said condenser intersecting the axis of said element at the center of curvature of said spherical surface; whereby the total luminous energy collected by said condenser is the sum of the direct radiation thereon from said element and the multiple reflections by said means of radiation from said

20 element, and approximates that of a black body at the same absolute temperature as said element.

25 3. An optical illuminating system having a high and uniform luminosity, comprising an incandescent element

30 constituting a source of radiation; an envelope containing said element; means of optical quality for forming a reflected image of said element strictly and exactly on said element, comprising a spherical optical surface of large dimensions perfectly centered on said element and having a radius such that spherical aberrations close to its center of curvature are substantially smaller than said element; said means including a lens providing said spherical

35 surface, a plane mirror positioned perpendicular to the axis of said lens to form an auto-collimator system on said element, and a colored glass element disposed between said mirror and said lens, said colored glass element being inclinable with respect to the axis of said auto-collimator system; and a condenser adapted to cooperate with said source of radiation; the axis of said condenser intersecting the axis of said incandescent element at the center of curvature of said spherical surface; whereby the total luminous energy collected by said condenser is the sum of the direct radiation thereon from said incandescent element and the multiple reflections by said means of

40 radiation from said element, and approximates that of a black body at the same absolute temperature as said incandescent element.

45 4. An optical illuminating system having a high and uniform luminosity, comprising an incandescent element

50 constituting a source of radiation; an envelope containing said element; means of optical quality for forming a reflected image of said element strictly and exactly on said element, comprising a spherical optical surface of large dimensions perfectly centered on said element and having a radius such that spherical aberrations close to its center of curvature are substantially smaller than said element; said means including a lens providing said spherical

55 surface, a plane mirror positioned perpendicular to the axis of said lens to form an auto-collimator system on said element, and a colored glass element disposed between said mirror and said lens, said colored glass element being inclinable with respect to the axis of said auto-collimator system; and a condenser adapted to cooperate with said source of radiation, the axis of said condenser intersecting the axis of said incandescent element at the center of curvature of said spherical surface; whereby the total luminous energy collected by said condenser is the sum of the direct radiation thereto from said incandescent element and the multiple reflections by said means of

60 radiation from said incandescent element, and approximates that of a black body at the same absolute temperature as said incandescent element.

65 5. An optical illuminating system having a high and uniform luminosity, comprising an incandescent element

70 constituting a source of radiation; an envelope containing said element; means of optical quality for forming a reflected image of said element strictly and exactly on said element, comprising a spherical optical surface of large dimensions perfectly centered on said element and having a radius such that spherical aberrations close to its center of curvature are substantially smaller than said element; said means including a lens providing said spherical

75 surface, a plane mirror positioned perpendicular to the axis of said lens to form an auto-collimator system on said element, and a colored glass element disposed between said mirror and said lens, said colored glass element being inclinable with respect to the axis of said auto-collimator system; and a condenser adapted to cooperate with said source of radiation, the axis of said condenser intersecting the axis of said incandescent element at the center of curvature of said spherical surface; whereby the total luminous energy collected by said condenser is the sum of the direct radiation thereto from said incandescent element and the multiple reflections by said means of radiation from said incandescent element, and approx-

imates that of a black body at the same absolute temperature as said incandescent element; said system further comprising an auxiliary mono-chromatic lamp for projecting reference marks of predetermined wave lengths on the continuous base derived from said incandescent element.

5. An optical illuminating system having a high and uniform luminosity, comprising an incandescent element constituting a source of radiation; an envelope containing said element; reflector means of optical quality in the path of visible radiation from said element for reflecting such radiation and forming a reflected image of said incandescent element strictly and exactly on said element, said means comprising a plurality of spherical mirror elements of the same radii having their radii centered on said source and being arranged symmetrically with respect to a plane of emission of radiation from said source; a spherical mirror having a smaller radius than said mirror elements; an emission window; the opening angle of said mirror being equal to the opening angle of said window; said mirror and said window lying across and being centered on said plane at opposite sides of said source; and a condenser for collecting radiation reaching said window, the axis of said condenser intersecting the axis of said incandescent element at the center of curvature of said mirror; whereby the total luminous energy collected by said condenser is the sum of the direct radiation thereto from said incandescent element and the multiple reflections by said reflector means of radiation from said in-

candescent element, and approximates that of a black body at the same absolute temperature as said incandescent element.

6. An optical system as claimed in claim 1, said reflector means being substantially non-diffusing to said radiation and having substantially the maximum possible reflecting power for said radiation.

7. An optical system as claimed in claim 1, said incandescent element being a single coiled tungsten element.

10 8. An optical system as claimed in claim 1, said incandescent element being a flat tungsten strip element.

9. An optical system as claimed in claim 1, said incandescent element being constituted by a plurality of coiled tungsten filaments.

15 10. An optical system as claimed in claim 1, said incandescent element being constituted by an electrical resistance rod filament.

11. An optical system as claimed in claim 1, said source of radiation being an opalescent lamp.
